CLAIM

The ornamental design for a sample carrier, as shown and described.

DESCRIPTION

FIG. 1 is a top, front end, right side perspective view of a sample carrier embodying our new design;

FIG. 2 is a front end elevation view thereof;

FIG. 3 is a rear end elevation view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines are included for the purpose of illustrating unclaimed surfaces of the sample carrier and form no part of the claimed design.

In a preferred embodiment, the nature of this product is a sample carrier for carrying samples in an atomizing furnace.
